(57) **CLAIM**

I claim the ornamental design for a water gun, as shown and described.

DESCRIPTION

FIG. 1 is a first perspective view of a water gun showing my new design;

FIG. 2 is a second perspective view of FIG. 1, viewed in another aspect;

FIG. 3 is a front view of the water gun;

FIG. 4 is a rear view of the water gun;

FIG. 5 is a left view of the water gun;

FIG. 6 is a right view of the water gun;

FIG. 7 is a top view of the water gun;

FIG. 8 is a bottom view of the water gun; and,

FIG. 9 is an exploded view of FIG. 1.

The broken lines depict portions of the water gun in which the design is embodied that form no part of the claimed design.
